ABSTRACT: A straight bar knitting machine has drawoff mechanism including endless chains having fabric- or welt-stick-engaging drawoff hooks for carrying a pressed-off fabric blank from the needles to normally open drawoff rollers and over an angular stripper plate, and wherein the stripper plate and the fabric thereon are gripped by the drawoff rollers which are rotated to advance the gripper plate and the fabric for stripping the fabric or the welt stick clear of the drawoff hooks.

STRAIGHT BAR KNITTING MACHINES

This invention is for improvements in or relating to straight bar knitting machines and concerns hook drawoff mechanism for garment blanks which are each in turn pressed-off the needles and which are started either by operation of a transfer point bar to transfer a rib welt to the needles or by production of a turned welt on the machine with the aid of a welt stick.

In a previously proposed drawoff arrangement of applicants, endless side chains carried a drawoff bar to which either a fabric hook bar or a welt stick hook bar could be fitted for drawoff of a garment blank either by point engagement with the fabric or by hook engagement with a welt stick, the garment blank being thus drawn off until the blank is pressed off the needles, and then being further drawn away from the needles passed downwardly directed brushes which were provided for stripping the garment blank from the drawoff points, or welt sticks hooks, by reverse travel of the endless side chains.

While this previously proposed arrangement has useful advantages over other prior arrangements, its efficiency, particularly in respect of the garment blanks being of different lengths including short length, and in respect of the stripping operation of the brushes, was found not to be as satisfactory as desired.

An object of the invention is to provide drawoff mechanism for pressed-off garment blanks, starting with transferred rib or turned welts, of such improved construction as to be satisfactorily efficient in use for different lengths of blanks.

This invention provides drawoff mechanism for pressed-off garment blanks, starting with transferred rib or turned welts, comprising endless side chains carrying fabric and/or welt-stick-engaging drawoff hooks, means for racking and continuously driving the endless side chains at different times, normally open fabric drawoff nip rollers to which the blanks are fed by the drawoff hooks, means for racking and continuously driving the nip rollers at different times, and an angular stripper plate adapted to be gripped at the underside of the blanks by closing of the drawoff nip rollers and to be displaceable by rotation of the latter to push the blanks off the drawoff points. Conveniently there is a racking mechanism for the endless side chains and for a lower nip roller and also a reversible rotating mechanism therefor, with means for switching from the former to the latter when required. Conveniently also the stripper plate is pivotally mounted in cooperation with a lower relatively stationary nip roller and normally held inoperative by a lost motion connection to an upper displaceable nip roller, with means for lowering the upper nip roller to close the nip when required and to then release, by the lost motion, the stripper plate for operation by rotation of the nip rollers. Means for lowering the upper roller conveniently consists of an electric motor driving a lead screw on which is a screwnut connected to the upper roller and which operates between spaced electric control switches for control of the upper and lower limits of travel of the upper roller.

Racking the endless side chains is conveniently through the medium of racking mechanism and chain and sprocket means, and continuously driving the endless side chains and the lower nip roller is conveniently through the medium of an electric motor and chain and sprocket means, and these means are under control of switch operated clutches.

For the instance of the transferred rib arrangement, the drawoff hooks conveniently engage the fabric underneath the latter in a straight run of the endless side chains, and for this purpose the hooks at this location have upwardly directed points such that when travelling downwards at the location of the lower drawoff roller, the points project forwards thereby providing for release of the fabric therefrom by a forward movement of the stripper plate.

In the instance of the turned welt arrangement, the drawoff hooks are conveniently recessed plates, and the welt stick is

released from the recesses at the time of operation of the stripper plate positively through a pushing action thereon by striker members depending from and carried downwardly by the upper roller.

5 The above and other features of the invention set out in the appended claims are incorporated in the construction which will now be described, as a specific embodiment with reference to the accompanying drawings in which:

FIG. 1 is a sectional side view of drawoff mechanism according to the invention.

FIG. 2 is a plan view of part of FIG. 1.

FIG. 3 is a sectional side view of part of the drawoff mechanism.

FIG. 4 is a side view of motor control means for part of the drawoff mechanism.

FIG. 5 is an end view of racking control means for the drawoff mechanism.

FIG. 6 is a detail end view of motor drive means for the drawoff mechanism.

FIG. 7 is a part sectional side view of FIG. 6.

FIG. 8 is a diagrammatic side view of the mechanism in use for the transferred rib arrangement.

FIG. 9 is an enlarged side view of the mechanism at an early stage in the drawoff operation.

FIG. 10 is a similar view to FIG. 9 at a later stage.

FIG. 11 is a similar view to FIG. 10 at a later stage. FIG. 12 is a similar view to FIG. 11 at a later stage.

FIG. 13 is a similar view to FIG. 8 showing the turned welt 30 drawoff arrangement. FIG. 14 is a similar view to FIG. 13 showing the turned welt drawoff arrangement at an early stage.

FIG. 15 is a similar view to FIG. 14 at a later stage.

FIG. 16 is a similar view to FIG. 15 at a later stage.

35 FIG. 17 is a similar view to FIG. 16 at a later stage.

FIG. 18 is a similar view to FIG. 17 at a later stage.

FIG. 19 is a detail view of a fabric control device of the mechanism.

40 FIG. 20 is a detail view of switch control means of the invention.

FIG. 21 is a side view of FIG. 20.

FIG. 22 is an enlarged sectional view of ratchet wheel and clutch control means.

45 FIG. 23 is an enlarged sectional view on line 23-23 of FIG. 7 with pawls inoperative.

FIG. 24 is a similar view to FIG. 23 with pawls operative.

FIG. 25 is an enlarged part sectional view of chain drive and clutch means.

50 Referring to FIG. 1 the work drawoff mechanism is in a straight bar knitting machine constructed and arranged for knitting nonrib garment blanks which are in turn pressed-off from the needles and which are of varying length such as for fronts, backs and sleeves of garments. In one arrangement production of the blanks is preceded by operation of a transfer point bar to transfer rib welts to the needles and in another arrangement the blanks are started by knitting a turned welt with the aid of a welt stick in known manner.

60 The machine is identified by usual knocking over bits 1, usual sinkers 2, and, for the rib transfer arrangement, a previously proposed transfer point bar 3, operated in previously proposed manner to transfer rib welts therefrom to the needles N, FIG. 9, for preceding production of successive blanks.

The drawoff mechanism, FIGS. 2, 3, for the blanks 65 comprises a pair of endless side chains 4, which are guided over upper sprocket wheels 6 to 9, to have an upper horizontal lap, and lower sprocket wheels and rollers 12 to 15 to have a lower lap. Bridging the chains 4, 5 and secured resiliently thereto is a drawoff hook bar 16 having a series of spaced drawoff hooks 70 17 with end points 17a which, when the hook bar 16 is travelling with the horizontal upper lap of the chains, are directed upwardly from the chains, when the hook bar is travelling downwardly with a downwardly travelling part such as 4a of the chains, are directed substantially horizontally from the chains, FIG. 10.

Mounted for rotation coaxially between the chains is a lower fabric drawoff roller 18, FIG. 3, which is secured to the shaft 19 on which the chain sprocket wheels 6, 8 are freely mounted, and for cooperating with this lower roller 18 there is an upper roller 20 carried by end stub axles 20a, 20b and end arms 21, 22 mounted freely on a shaft 23. Also on the shaft 23 are short end arms 24, 25 connected by links 26, 27 to short end arms 28, 29 with slotted connections such as 30, and similar short end arms 31, 32 on the shaft 23 have pegs 33, 34 projecting under the arms 21, 22.

Also mounted on the end stub axles 20a, 20b are striker fingers 20c, 20d, for a purpose to be hereinafter referred to. The short end arms 28, 29 are mounted on a shaft 35 on which are also mounted arms such as 36 carrying end finger plates 37, 38 by pivotal connections such as 39, and the finger plates are spring controlled by leaf springs such as 40 mounted on the pivotal connections such as 39 and having one arm slidably engaged with a peg 42, 43 on the finger plates 37, 38 and another arm slidably engaged with a peg such as 45 on the short end arms 28, 29.

Mounted on and extending between the end finger plates 37, 38 is a stripper plate 46. Both end finger plates 37, 38 and the stripper plate 46 have horizontal portions just below the level of the upper lap of the chains 4, 5, the horizontal portion also extending just over the lower roller 18, and downwardly curved portions of the end finger plates and the stripper plate follow the contour of the lower roller 18 as shown for 37, 46 in FIG. 9.

For lowering the upper roller 20 to the lower roller 18, and onto the stripper plate 46; the shaft 23 has on it an arm 47, FIG. 1, connected by a link 48 to a screwnut 49a, also FIG. 4, on a lead screw 49 which is rotatable by a reversible motor 49b under control of limit switches SW1, SW2 which are secured to brackets 49f, 49c at opposite ends of the lead screw 49 to be operated by screwnut abutments 49d, 49e on the screwnut 49a at the ends of the latter's travel.

The chains 4, 5 and the lower roller 18 are adaptable for racking and continuous motion, at different times, by mechanism particularly of FIG. 5 to 7 which show broken end parts of the shaft 19 and 35.

For the racking of the lower roller 18, the shaft 19 has an extension 19a, FIGS. 7, 22, on which is one part 50a of an electromagnetic clutch 50, the other part 50b of which is on a sleeve 19b which is free on the shaft extension 19a and is operable by a switch operated by a cam of a known timing cam device which is operative in known manner in the periods between the press-off of one fabric and starting the next fabric. The shaft 19 is adapted to be racked round by pawls 51 operating on a ratchet wheel 52, FIGS. 5, 7, and 23, 24, the pawls 51 being of different lengths for fine adjustment motions and carried by a rocking operator plate 53 connected by a link 54 to a cam follower lever 55, FIG. 1, engaging a cam 56 on the machine's main camshaft 57. This racking is under control of a rocking control plate 58, FIG. 5, carrying a control bit 59 for moving under the pawls 51 to raise them clear of the ratchet wheel 52, FIG. 23, or away from the pawls 51 for engaging the ratchet wheel 52, FIG. 24, and the rocking control plate 58 is operable through a link 60 between it and a lever 61 pivoted to a bracket 62, FIG. 1, and lever 61 being connected at one end by a link 63 and connecting means 63a to a control lever 63b operable by a disc control cam 63c on the machine's top disc control camshaft 63d, so that a pull on the link 63 renders the pawls 51 ineffective. The pawls are maintained ineffective for desired periods by a prop 64 being engageable under a projection 58a on the rocking control plate 58, the prop 64 being pivotally mounted on the bracket 62 and being connected by a link 65 to a feeler arm 65a which is mechanically operated in known manner by a known punched chart programming means P. The racking is initially effective on the sleeve 19b, FIGS. 7, 22, through the intermediary of a sleeve 52a interconnecting the ratchet wheel 52 and the sleeve 19b, and is timed when required, by the timing cam operation of the switch for the clutch 50, to become effective on the

shaft 19 and the lower roller 18 for a purpose to be hereinafter referred to.

For forward racking of the chains 4, 5, as distinct from their continuous or rearward operation, the sleeves 52a, 19b, FIGS. 5, 7, 22, have connected to them, for rotating by the ratchet wheel 52, a sprocket wheel 66 which is connected by a chain 67 to a sprocket wheel 68. However, this sprocket wheel 68, FIG. 25, is free on a shaft 69 so that this shaft 69 is not at this stage rotated. The shaft 69 is connected to the chain drive shaft 35 by sprocket wheels 70, 71 and chain 72. On the shaft 69 is one part 73a of an electromagnetic clutch 73 the other part 73b of which is on a sleeve 68a carrying the sprocket wheel 68 and free on the shaft 69. This clutch part 73b is operable by an outer limit stop switch L1, FIGS. 1, 20, 21, when closed by a stud 90a on a chain 90 which is driven by reverse rotation of the shaft 35 which drives the chains 4, 5, in reverse after a previous operation so that the switch L1 is closed when the hook bar 16 is fully advanced. Thus forward racking is initially effective on the clutch part 73b and is rendered effective on the shaft 35 by the switch operation of the clutch 73 when required as hereinafter referred to.

For continuous operation of the lower roller 18 and the chains 4, 5 when required, as will be referred to hereinafter, there is a reversible motor 74, FIGS. 6, 7, driving a shaft 75 on which is one part 76a of an electromagnetic clutch 76 the other part 76b of which is on a sleeve 77 and is operable by a cam of the timing device. The sleeve 77 carries a sprocket wheel 78, and this sprocket wheel 78 is connected by a chain 79 to sprocket wheel 80 on the sleeve 68a of the clutch 73. Consequently when the clutch 76 is operated by the timing cam operated switch, this clutch is engaged and, combined with the clutch 73 engaged by operating the switch L1, causes the motor 74 to drive the chains 4, 5, and combined with the clutch 50 made by a cam of the timing device, causes the motor to drive the lower roller 18.

There is further provided at the front of the drawoff chains 4, 5, a fabric takeoff deflector rod 81, FIGS. 1, 2 and 19, which is secured at one end to a short arm 82 mounted on a pivot 83 supported by a bracket 84 secured to a frame part 85 of the machine. Secured on the pivot 83 is a sleeve 86 to which is attached a lower end of a chain 87 the upper end of which is attached to a short arm 88 secured on the shaft 23, so that raising and lowering of the roller 20 is accompanied by raising and lowering of the deflector rod 81 during which the chain 87 winds on and unwinds off the sleeve 86, for a purpose to be hereinafter described.

In operation of the mechanism for the instance of starting with a rib welt, it will be assumed that the previous garment piece has been pressed-off and drawn off by the chains 4, 5 and roller 18. At this stage the link 63, FIG. 5, is pulled by the control disc 63c on the top disc control shaft 63d to move the control bit 59 under the racking pawls 51 and raise the latter clear of the ratchet wheel 52, and the reversible motor 49b, FIG. 1, is switch operated, by a cam of the timing device, to reverse the current through the motor, in known manner to reverse the motor, for the motor to raise the upper roller 20, FIG. 1, to its raised position as shown at 'E' in FIG. 8. The motor 49b is then stopped by the lower switch SW2, FIG. 4, and the clutch 50 is disengaged by a cam of the timing device. The control bit 59 is held operating by the prop 64, FIG. 5. The reversible motor 74, FIG. 7, is switch operated in reverse by a cam of the timing device in like manner to the motor 49b. The clutch 76 is switch operated to engage by a cam of the timing device, and the clutch 73 is operated to engage by the timing device so that the chains 4, 5 are returned in a continuous motion to their starting positions with the hooks 17 adjacent the needles 'N' as shown diagrammatically at 'A' in FIG. 8. Then the clutch 76 is switch operated by an inner limit switch L2, FIGS. 20, 21, operated by a stud 90b on the chain 90 to disengage, and the motor 74 is stopped by a switch operated by a cam of the timing device.

The new rib welt RW, FIG. 9, is transferred to the needles 'N' in the previously proposed manner by use of the transfer

bar 3, FIG. 1, and the drawoff hooks 17 are engaged in the rib welt RW as shown in FIG. 9.

As fabric is knitted onto the rib welt RW, the chains 4, 5 are racked by the racking mechanism, FIGS. 5, 7, through the link 54, FIG. 5, racking being started by the link 63 being pulled by programming means to pull out the prop 64, so that with the clutch 73 engaged and the clutches 50 and 76 disengaged, the racking is imparted to the chain driving shaft 35.

On completion and pressing-off of the garment piece, the timing device starts in known manner, and assuming that the garment piece is comparatively short, so that the hook bar 16 has not at the time of press-off reached its fully out position so that the outer limit stop switch L1 is not operated, the racking is stopped by a pull on the link 63 from the top disc control shaft 63d, to move the control bit 59 under the pawls 51, and the clutch 76 is switch operated to "engage" and the motor 74 is switch operated to start, by cams of the timing device, so that further motion of the chains 4, 5 is continuous from the motor 74. The chains 4, 5 therefore carry the hook bar 16 rapidly between the rollers 18, 20 to a position, FIG. 10, whereat the outer limit stop switch L1 is operated by the stud 90a which causes the clutch 73 to disengage and introduces the motor 49b, FIG. 4, to lower the upper roller 20, as shown in FIG. 11, onto the rib welt RW over the stripper plate 46 and roller 18, the motor being then stopped by the switch SW1, FIG. 4.

The clutch 50 becomes switch operated by the outer limit stop switch L1 to 'engage' so that the operating motor 74 now drives the bottom roller 18 which also drives the upper roller 20, and the result is that the rib welt RW and the stripper plate 46 are together carried by the rollers 18, 20, assisted by the spring means 40, through the nip thereof to the projected position shown in FIG. 12. In thus moving to this projecting position, as guided by the bracket 36, the stripper plate 46 carries the rib welt RW off the horizontally disposed hook points 17a as shown, and continued rotation of the rollers 18, 20 acts on the rib welt RW only to deliver it completely through the nip from where the rib welt RW fails towards a container.

In the instance of the rib welt RW being of comparatively long length such for example that the hook bar 16 is racked to the outer limit stop switch L1 before the press-off from the needles, the operation of the outer limit stop switch L1 acts as before to cause lowering of the upper roller 20, by the motor 49b, and to stop racking of the chains by disengaging the clutch 73. However instead of the rollers being thereupon continuously rotated, they are racked, by "engagement" of the clutch 50 by the outer limit stop switch L1 (clutch 76 having been originally disengaged), to continue drawing-off the rib welt RW and the fabric being knitted and to project the stripper plate 46 which strips the rib welt RW from the hook points 17a as before, and upon pressing-off of the rib welt RW and fabric from the needles, the rollers 18, 20 are converted to continuous rotation by the top disc control cam operating the link 63 to stop the racking and by the clutch 50 remaining engaged for driving by the motor 74, with clutch 76 engaged by a cam of the timing device, until the hereinbefore-described cycle of operations have been carried out.

In the instance of starting with a turned welt the hook bar 16 is not in use, and the drawoff is effected, as indicated diagrammatically in FIG. 13, by use of the usual welt stick WS, suitably applied by delivery arms in well-known manner and becoming engaged by hook plates such as 4b, FIG. 14, on the chains 4, 5.

In the initial drawoff racking motion of the chains, the hook plates 4b not only engage the welt stick WS but also draw it out of engagement with its delivery arms which are then able to return to their inoperative position. During turning of the welt, FIG. 14, the racking is stopped by top disc cam control of link 63, motor 74 is operated in reverse by a switch operated by a disc on the top disc shaft and the clutch 76 is switch operated, through a first switch operated by a cam on the top disc shaft and a second timing switch operated by a cam on the main shaft, to be engaged for a short time and then

disengaged, so that this causes reverse motion of the chains and hook plates for easing tension on the welt to allow for the turn of the welt. Fabric is knitted onto the welt TW, FIG. 15, and is further drawn off by the chains and hook plates 4b.

5 In the instance of a comparatively short turned welt TW such that it is completed prior to the hook bar reaching the outer limit stop switch L1, the press-off operation causes by the timing device change from racking of the chains to continuous motion, as for the rib welt RW, for carrying the welt rapidly through the open rollers 18, 20 until a fully out position is reached, FIG. 16. In the meantime the outer and inner limit switches L1, L2 have been rendered ineffective by known means and further outer and inner limit switches L3, L4 are rendered effective by known means to be operable by cam bits 90c, 90d on the chain 90. Therefore, with the welt in the fully out position, the limit stop switch L3 is operated to start the motor 49b so that the upper roller 20 is lowered to trap the welt TW between it and the stripper plate 46 on the lower roller 18, whereupon the motor is stopped, as before. The upper roller 20 carries the end striker fingers such as 20c with it which pushes against the welt stick WS as shown in FIG. 17 to release it from the hook plates. Following this, continued rotation of the rollers is effected, as for the comparatively short rib welt RW, to project the stripper plate 46 which carries with it the turned welt TW and the welt stick quite clear of the hook plates 4b, and to finally release the turned welt TW to fall towards a container.

In the instance of the turned welt TW being of comparatively long length, the drawoff and stripping is modified in substantially similar manner as for the comparatively long rib welt RW.

The operated parts are returned as before eventually under control of the inner limit switch L4 instead of L2.

35 As shown in FIG. 12, when the roller 20 has been lowered for drawing off the fabric, the rotation of the shaft 23 raises the arm 88 to the full line position in which the chain 87 rotates the sleeve 86 and pivot 83 thereby to raise the deflector rod 81 to the elevated position shown in which it is maintained throughout the drawoff by the rollers 20, 18. At this stage the fabric is released for falling to a container as hereinbefore referred to, but the fabric is still connected by trailing yarn to the thread carrier so that the drawn off fabric does not immediately fall into the container. In the meantime the roller 40 20 is raised, the stripper plate 46 is retracted and the chains are retracted carrying the hooks 17 with them, and it is to ensure that the hooks do not thereupon reengage with the fabric that the deflector rod 81 is provided. It will be understood that when the roller 20 is raised, the chain 87 slackens, and the deflector rod 81 thereupon lowers by gravity, first onto the fabric on the projected stripper plate 46 until the latter is retracted whereupon the deflector rod falls further and carries the fabric downwardly with it clear of the hooks 16, during which the trailing yarn may be drawn through the thread carrier and/or from waste courses on the trailing end of the fabric.

50 55 What we claim is:

1. Drawoff mechanism for pressed-off garment blanks, comprising endless side chains carrying drawoff hooks, means for racking and continuously driving the endless side chains at different times, fabric drawoff nip rollers to which the blanks are fed by the drawoff hooks, means for opening and closing the nip rollers, means for racking and continuously driving the nip rollers at different times, and an angular stripper plate adapted to be gripped at the underside of the blanks by closing of the nip rollers and to be displaceable by rotation of the latter to push the blanks off the drawoff points.

60 65 70 75 2. Mechanism according to claim 1 wherein there is a racking mechanism for the endless side chains and for a lower nip roller and also a reversible rotating mechanism therefore, with means for switching from the former to the latter when required.

3. Mechanism according to claim 1 wherein the stripper plate is pivotally mounted in cooperation with a lower relatively stationary nip roller and normally held inoperative by a

lost motion connection to an upper displaceable nip roller, with means for lowering the upper nip roller to close the nip when required and to then release, by the lost motion, the stripper plate for operation by rotation of the nip rollers.

4. Mechanism according to claim 1 wherein means for lowering the upper roller consists of an electric motor driving a lead screw on which is a screwnut connected to the upper roller and which operates between spaced electric control switches for control of the upper and lower limits of travel of the upper roller.

5. Mechanism according to claim 1 wherein racking the endless side chains is through the medium of racking mechanism and chain and sprocket means, and continuously driving the endless side chains and the lower nip roller is through the medium of an electric motor and chain and sprocket means, and these means are under control of switch operated clutches.

6. Mechanism according to claim 1 wherein for the instance of a transferred rib arrangement, the drawoff hooks engage the fabric underneath the latter in a straight run of the endless

side chains, and for this purpose the hooks at this location have upwardly directed points such that when travelling downwards at the location of the drawoff rollers, the points project forwards thereby providing for release of the fabric therefrom by a forward movement of the stripper plate.

7. Mechanism according to claim 1 wherein in the instance of a turned welt arrangement, the drawoff hooks are recessed plates to receive a welt stick, and the welt stick is released from the recesses at the time of operation of the stripper plate positively through a pushing action thereon by striker members depending from and carried downwardly by the closing of the nip rollers.

8. Mechanism according to claim 1 having a fabric drawoff deflector arm, means for holding the deflector arm in an upper inoperative position across the front of the machine, and means for releasing the deflector arm at required time to provide for the arm lowering to carry the fabric with it to a low location.
